LUBRICANT COMPOSITION

This is a continuation of application Ser. No. 07/546,277, filed on Jun. 28, 1990, now abandoned.

The present invention relates to lubricant compositions which are stabilized against oxidative degradation. Stabilization is effected by the incorporation of at least two specific additives.

It is known and conventional to incorporate additives into lubricants based on mineral oils or synthetic oils in order to improve their general use properties. Additives for stabilizing lubricants against oxidative degradation, known as antioxidants, are especially important. The oxidative degradation of lubricants is particularly significant in the case of engine oils, because high temperatures prevail in the combustion chamber of engines and, as well as oxygen, nitrogen oxides (NO_x) are present and act as oxidation catalysts.

The antioxidants used for lubricants are, in particular, organic sulfur and phosphorus compounds and also aromatic amines and phenols, especially sterically hindered phenols (see e.g. Ullmanns Encyklopädie der technischen Chemie (Ullmann's Encyclopaedia of Chemical Technology), 4th edition, Verlag Chemie, volume 20 (1981), page 541-43).

Sterically hindered amines have also already been proposed as stabilizers for lubricating oils, e.g. in U.S. Pat. No. 4,069,199 or JP-A-85/28496.

EP-A-356 677 has proposed mixtures of aromatic amines and sterically hindered amines as antioxidants for lubricants, it also being possible for phenolic antioxidants to be added to these mixtures.

It has been found that combinations of phenolic antioxidants with sterically hindered amines are outstandingly suitable for the stabilization of lubricants, even without the addition of aromatic amines.

The present invention relates to a lubricant composition comprising

- (A) a mineral or synthetic oil or a mixture of such oils,
- (B) at least one sterically hindered amine and
- (C) at least one phenol of formula I

wherein A is hydrogen, $\text{C}_1\text{-C}_{24}$ alkyl, $\text{C}_5\text{-C}_{12}$ cycloalkyl, $\text{C}_7\text{-C}_9$ phenylalkyl, phenyl or a group $-\text{CH}_2\text{-S-}$ R^1 or

EXAMPLE 6

The oxidation resistance of the oils stabilized according to Example 5 is determined by the following methods:

Under 10 bar of oxygen. The time at which the exothermic reaction begins, T_B (induction time), and the time at which the exothermic reaction ends, T_E , are measured: the longer the induction time, the higher the oxidation resistance. The stabilizers used are the phenolic antioxidants P-1 and P-2 and also:

P-3: the reaction product of 160 g of 2,6-di-tert-butylphenol, 40 g of 2-tert-butylphenol, 5.8 g of KOH, 50 ml of ethanol and 24 g of paraformaldehyde at 80° C., containing the following main components:

EXAMPLE 7

The oxidation resistance is tested in a differential scanning calorimeter as in Example 6, except that the measurements are made under 8 bar of air with which 380 ppm of (NO)_x have been mixed, rather than under oxygen, and the isothermal temperature is 170° C.
